UNITED STATES PATENT OFFICE.

JOHN T. JOHNSON AND NEWTON T. SMITH, OF GRAND RAPIDS, MICHIGAN.

IMPROVEMENT IN CAR-COUPINGS.

Specification forming part of Letters Patent No. 41,924, dated March 15, 1864.

To all whom it may concern:

Be it known that we, JOHN T. JOHNSON and NEWTON T. SMITH, of Grand Rapids, in the county of Kent and State of Michigan, have invented a new and Improved Car-Coupling; and we do hereby declare that the following is a full, clear, and exact description of the same, reference being had to the accompanying drawings, making a part of this specification, in which—

Figure 1 is a plan or top view of our invention; Fig. 2, a side sectional view of the same, taken in the line xx , Fig. 1; Fig. 3, a perspective view of a portion of one of the draw-heads.

Similar letters of reference indicate corresponding parts in the several figures.

To enable those skilled in the art to fully understand and construct our invention, we will proceed to describe it.

A represent two draw-heads, which may be of the usual or an approximate form, and provided each with a plate, B, which projects from a shaft, C. These shafts C are fitted horizontally and transversely in the draw-heads, the bearings of the shafts being in the sides of the draw-heads, and the bearings A at one side of the draw-heads being of oblong form and sufficiently long to admit of the plates B being passed through them into the draw-heads. (See Fig. 3.) The shafts C are retained in proper position within the bearings d by means of keys or pins b', which pass vertically into the draw-heads and through the bearings d, in contact with the shafts C, as will be fully understood by referring to Fig. 3.

In each draw-head A there is secured a spring, D. These springs may be of flat form and they are secured to the upper sides of the draw-heads by bolts b'. These springs bear upon the upper surfaces of the plates B, and have a tendency to keep the lower ends of the latter pressed downward, as will be fully understood by referring to Fig. 2.

The plates B have an inclined position in the draw-heads A, their lower ends projecting back within the draw-heads.

E represents a link or shackle, which has a shoulder, c, at each end, and against which the lower ends of the plates B bear when the draw-heads are connected by the shackle. This link or shackle has a rod, F, attached to it at about its center, said rod projecting

downward and having a chain, d, attached to it by which the link or shackle may be secured and disengaged from the plates B and draw-heads.

From the above description it will be seen that if one end of the link or shackle is thrust into either draw-head, the plate B in the draw-head into which the link or shackle is forced, will catch behind the shoulder c, and the link or shackle will be retained in the draw-head and also held in a horizontal position by the pressure of the plate B upon it, so that the link or shackle may enter the other draw-head.

When both ends of the link or shackle are secured in the draw-heads, the latter are connected together, as will be seen by referring to Fig. 2.

The shafts C of the plates B project at one end through the draw-heads, in order to admit of a key being applied thereto to raise the plates and release the link or shackle. One of these shafts C projects through the right-hand side of its draw-head and the other through the left-hand side of its draw-head, as shown in Fig. 1. By this means the link may be detached at either side of the draw-heads. Thus it will be seen that the link or shackle may be disconnected from the draw-heads in two different ways.

This coupling will admit of the ordinary link and pins being used by having pin-holes d' made vertically through the draw-heads and plates B, as shown in Fig. 2, and the improvement may be applied to the ordinary draw-heads in common use.

The plates B may be of sufficient weight to drop and work by their own gravity. In this case the springs D may be dispensed with.

Having thus described our invention, what we claim as new, and desire to secure by Letters Patent, is—

The combined arrangement of the obliquely-pivoted plates B, having apertures d', and projecting key-shafts C, with the draw-heads D and link E, in the manner herein shown and described.

JOHN T. JOHNSON.
NEWTON T. SMITH.
